CLAIM

The ornamental design for a travel pill organizer, as shown and described.

DESCRIPTION

FIG. 1 is a top perspective view of a travel pill organizer, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is a top perspective view of another embodiment;

FIG. 11 is a bottom perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is an enlarged detail view of area 18 in FIG. 10.

The broken lines depict portions of the article that form no part of the claimed design; the dash-dot-dash broken lines in the drawings show the encircling of the enlarged views and form no part of the claimed design thereof.

1 Claim, 18 Drawing Sheets
